UNITED STATES PATENT OFFICE

99,155

DESIGN FOR AN ELECTRICALLY-OPERATED CREAM SEPARATOR

Samuel T. Castleman, Louisville, Ky.

Application February 20, 1935, Serial No. 55,500

Term of patent 14 years

To all whom it may concern:

Be it known that I, Samuel T. Castleman, a citizen of the United States and a resident of Louisville, in the county of Jefferson and the State of Kentucky, have invented a new, original, and ornamental Design for an Electrically-Operated Cream Separator, of which the following is a specification, reference being had to the accompanying drawing, forming a part thereof, in which

Fig. 1 is a side elevation of an electrically-operated cream separator, showing my new design; and Fig. 2 is a front elevation thereof.

I claim

The ornamental design for an electrically-operated cream separator, as herein shown.

SAMUEL T. CASTLEMAN.
